UNITED STATES PATENT OFFICE.

JOHN NELSON AND ALBERT SCHEIWER, OF ERIE, PENNSYLVANIA.

CUE-TIP.

1,312,198.

Specification of Letters Patent.

Patented Aug. 5, 1919.

Application filed January 25, 1919. Serial No. 273,060.

To all whom it may concern:

Be it known that we, JOHN NELSON and ALBERT SCHEIWER, citizens of the United States, residing at Erie, in the county of Erie and State of Pennsylvania, have invented certain new and useful Improvements in Cue-Tips, of which the following is a specification, reference being had to the accompanying drawings.

10 This invention relates to certain improvements in cue tips, and it is an object of the invention to provide a tip of this character which possesses a maximum of efficiency, and which may be assembled in a convenient and effective manner.

It is also an object of the invention to provide a novel and improved cue tip which closely imitates the well known ivory type of tip, and wherein the cue proper is provided with a stem or shank with which is threadedly engaged a metallic sleeve or bushing, to the outer ends of which shank and sleeve the tip proper is secured by a suitable binder.

25 An additional object of the invention is to provide in a structure of this general character a sleeve adapted for engagement with the cue, and which sleeve has its outer end or edge knurled or otherwise roughened 30 to facilitate the retention of the tip proper in applied position.

The invention consists in the details of construction and in the combination and arrangement of the several parts of our improved cue tip whereby certain important advantages are attained and the device rendered simpler, less expensive and otherwise more convenient and advantageous for use, as will be hereinafter more fully set forth.

40 The novel features of our invention will hereinafter be definitely claimed.

In order that our invention may be the better understood, we will now proceed to describe the same with reference to the accompanying drawings, wherein:

Figure 1 is a fragmentary view in elevation of a cue having a tip applied thereto in accordance with an embodiment of our invention;

50 Fig. 2 is a longitudinal sectional view taken through the structure as illustrated in Fig. 1 with the tip proper in elevation; and

Fig. 3 is a view in top plan of the sleeve as disclosed in the preceding figures.

55 As disclosed in the accompanying drawings, C denotes a cue of any preferred type

as generally employed in connection with the game of billiards or pool, and the tip end of said cue C at its axial center is provided with an outwardly directed shank or 60 stud 1 having its periphery threaded.

S denotes an internally threaded sleeve, preferably formed of steel, and which is adapted to be arranged upon the stud or shank 1 and said sleeve is of a length equal 65 to the length of the stud or shank 1 so that when the sleeve S is properly applied, the outer end of said sleeve is flush with the outer end of the stud or shank 1.

The outer end or edge 2 of the sleeve S is 70 knurled or otherwise roughened so that the adhesion of the binder disposed over said outer end or edge and the outer end of the stud or shank S will effect a secure attachment of the tip T. The tip is preferably 75 leather, although any other material may be used which can be employed with the same facility.

The periphery of the sleeve S has applied thereto a coating 3 of porcelain or analogous 80 material, so that when the sleeve S and tip T are in applied position, the sleeve S will address the eye as formed of ivory or ivory substitute as is now generally employed.

It is believed to be self evident that by 85 employing a metallic sleeve S the life of the cue will be prolonged, so that the possibility of breaking or splitting of the sleeve S is avoided and said sleeve may be applied or removed with convenience and facility with 90 out the necessity of applying heat or other operations as is now required in connection with cue tips of the type now generally in use.

In addition to the material advantages 95 afforded by the metallic sleeve S, it is also to be noted that by having the outer end of the stud or shank 1 and the outer end or tip of the sleeve S substantially flush the maintenance of the tip T in applied position 100 through the character of binder or cement as now employed is further facilitated not only by the wood of the cue C proper but by the knurled outer face or end 2 of the sleeve.

105 From the foregoing description, it is thought to be obvious that a cue tip constructed in accordance with our invention is particularly well adapted for use by reason of the convenience and facility with which 110 it may be assembled and operated, and it will also be obvious that our invention is

susceptible of some change and modification without departing from the principles and spirit thereof, and for this reason we do not wish to be understood as limiting ourselves 5 to the precise arrangement and formation of the several parts herein shown in carrying out our invention in practice except as hereinafter claimed.

We claim:

- 10 In combination, a cue having its tip end provided with a longitudinally disposed threaded stud, a metallic sleeve engaged with said stud, said sleeve and stud being substantially of the same length so that when the 15 sleeve is applied on the stud, the outer end

of the stud and the outer edge of the sleeve are flush, a coating of porcelain engaged with the periphery of the sleeve, and a tip cemented to the outer ends of the assembled stud and sleeve, the outer end of the sleeve 20 being knurled to facilitate the cementing of the tip thereto.

In testimony whereof we hereunto affix our signatures in the presence of two witnesses.

JOHN NELSON.
ALBERT SCHEIWER.

Witnesses:

ADAM ESSER,
JOHN GELLNER.
